[57] CLAIM

The ornamental design for a golf club head having face insert, as shown and described.

DESCRIPTION

FIG. 1 is a perspective view of a golf club head having face insert embodying our new design;

FIG. 2 is a top plan view of the golf club head having face insert shown in FIG. 1;

FIG. 3 is a front elevational view of the golf club head having face insert shown in FIG. 1;

FIG. 4 is a bottom plan view of the golf club head having face insert shown in FIG. 1;

FIG. 5 is a rear elevational view of the golf club head having face insert shown in FIG. 1;

FIG. 6 is a toe end view of the golf club head having face insert shown in FIG. 1; and,

FIG. 7 is a heel end view of a golf club head having face insert shown in FIG. 1.

The characteristic feature of our design resides in a particular shape for the outer profile of the face insert for a golf club head, as shown.
